COMBINED SEAL CUTTER AND BOTTLE CAP REMOVER

Harvey A. Brownson, Baltimore, Md.

Application September 14, 1956, Serial No. 42,934

Term of patent 14 years

(Cl. D44—29)

Fig. 1.

Fig. 2.

Fig. 3.

*Fig. 2.*Fig. 1 is a side elevation of a combined seal cutter and bottle cap remover, showing my design;

Fig. 2 is a side elevation of the side opposite the one shown in Fig. 1;

Fig. 3 is a cross-section taken along line 3—3 of Fig. 2; and

Fig. 4 is a top perspective view of the combined seal cutter and bottle cap remover.

I claim:

The ornamental design for a combined seal cutter and bottle cap remover, as shown.
